SPARK-PLUG.

1,305,660.

Specification of Letters Patent. Patented June 3, 1919.

Application filed May 15, 1918. Serial No. 234,869.

To all whom it may concern:

Be it known that I, EMARSON E. MAIN, a citizen of the United States, residing at Indianapolis, in the county of Marion and

5 State of Indiana, have invented a new and useful Spark-Plug, of which the following is a specification, reference being had to the accompanying drawings and to the letters and figures of reference marked thereon.

0 This invention relates to a device that is used in connection with an explosion engine as one of the elements of the ignition systems thereof wherewith a jump spark is obtained for igniting the fuel or explosive mixture to actuate the engine, the invention having reference more particularly to a spark plug that is designed more especially for use in connection with the higher power explosion engines having standard 15 sizes of sockets or holes to receive the spark plugs.

An object of the invention is to provide a spark plug of the above-mentioned character that shall be so constructed as to afford 20 the maximum sparking capacity within the range of the standard size adopted for spark plugs.

Another object is to provide an improved spark plug which shall be so constructed as to be 25 reliable in operation and not be liable to become deranged or damaged either in handling or in use.

A further object is to provide improved electrodes in spark plugs which shall not 30 be liable to deteriorate or become unreliable because of carbon deposits thereon.

A still further object is to provide a spark plug of such construction as to be adapted to be operated without becoming 35 excessively heated, an aim being to keep the temperature of the spark plug down to the minimum in order to insure reliability and maximum efficiency and also long life of the spark plug.

40 With the above-mentioned and other objects in view, the invention consists in improvements in a spark plug generally and more particularly in novel electrodes and also in a feature whereby to cool the spark plug; and, the invention consists also further in the novel parts, and in the combinations and arrangements of parts, as herein- 45 after particularly described and further defined in the accompanying claims.

50 Referring to the drawings, Figure 1 is a side elevation of the spark plug con-

structed substantially in accordance with the invention; Fig. 2 is a section on the line II-II in Fig. 1; Fig. 3 is a bottom plan of the spark plug; Fig. 4 is a section of 60 parts separate from the other parts of the spark plug; and Fig. 5 is a fragmentary reproduction of a portion of Fig. 2 on an enlarged scale.

Similar reference characters on the different figures of the drawings indicate like parts or features of construction herein-after referred to in detail.

On the drawings the numeral 1 indicates the metallic body or shell of the improved 70 spark plug and it has a shank 2 on one end thereof which may be of the adopted standard external dimensions to enter the aperture with which the explosion engine is usually provided. The normal upper 75 portion of the body has a chamber 3 therein from which a bore 4 extends through the body and into the shank, the lower portion of the shank having a relatively smaller bore 5 communicating with the bore 4, so that 80 the body is hollow throughout. The shank has the usual external screw threads 6 thereon whereby to secure the body in place. The shank has a continuous beveled face 7 therein extending from the bore 5 and flaring outward to the end of the shank and this constitutes an annular negative or side electrode which affords a very wide pole or point at which the jump spark may be produced at any point along the length of the 85 electrode surface, and therefore in case one point is obstructed or for any reason rendered inefficient the spark may occur at another point.

A core 8 composed of suitable material 90 to constitute an electrical insulator is arranged partially in the hollow body or shell and has a collar 9 thereon which is arranged in the chamber 3 and seated upon a packing washer 10 on the bottom of the 100 chamber; and a washer or gasket 11 is arranged upon the outer end portion of the collar and engaged by a bonnet ring 12 composed of a pressed down or spun portion of the body or shell to secure the insulator 105 in place. The insulator or core has a neck portion 13 extending downward into the bore 4. The core 8 has a bore or channel 14 extending therethrough and in which is a lining 15 of cement which may be of more 110 or less extent. A conducting stem or rod 16 is arranged in and extends through the

bore 14 and has external screw threads 17 extending from one end thereof, some of the screw threads being in the bore 14 and embedded in the cement 15 for securing the 5 stem to the core; and, in some cases the stem may have a collar 18 thereon engaging the end of the neck 13 of the core. Preferably a nut 19 or facing washer is arranged on the stem 16 and seated on the top of 10 the core 8, a terminal nut 20 being seated on the nut or washer 19. The nut has a bore 21 receiving the upper end of the stem 16 and provided with screw threads 22 engaging the screw threads 17, the nut preferably 15 having a relatively smaller aperture 23 extending through it from the bore. The nut has a circumferential groove 24 therein to receive the standard snap terminal whereby to connect a circuit wire to the nut 20 and thereby with the stem 16.

A novel positive or center electrode 25 is provided which is disk-shaped and arranged within the annular side electrode 7, the top 26 of the positive electrode being 25 convex and integrally connected to the lower or inner end of the stem 16, the peripheral edge 27 of the positive electrode being greater in diameter than the bore 5 of the shank and arranged adjacent to but 30 separate from the larger outer portion of the annular electrode 7, so that an improved annular gap is provided between the two electrodes and permitting a jump spark to be produced at any portion of the gap.

The center electrode 25 preferably has apertures 28, 28' therein to permit free passage of air or gases and also to permit oil to readily flow down from the interior or bore of the shank 2 in case oil is received 40 into the shank.

The lower or outer face of the disk is preferably made flat and in practice it has been found that the best results are obtained when the upper or inner face of said disk 45 is slightly coned, that is the conical surface being from 30° to 40° from the horizontal. By giving the upper surface this form and providing the disk with apertures or openings it has been found that all accumulation 50 of carbon is prevented owing to the fact that during the alternate compression and suction strokes of the piston the gases will pass freely back and forth through and around the disk completely removing any accumulations. The substantially flat face of the disk 55 will also aid in keeping the plug free of carbon for the reason that when the said face becomes heated any oil thrown into contact therewith will be immediately thrown off inasmuch as the flat face does not provide an opportunity for lodgment.

For the purpose of cooling the center electrode or keeping its temperature down to the minimum degree, a cooling system therefor is provided and preferably is associated 60

with the conducting stem 16 which in this case has a bore 29 therein extending from its upper end nearly to the disk or electrode 25, so that heat may be radiated from the electrode to the atmosphere, the bore permitting cool air to descend and heated air to ascend therein. In some cases a liquid substance 30, such as mercury, is placed in the bore 29, in such case the bore preferably having a suitable closure 31 in its upper portion; and, the opening 23 in the nut 20 preferably has a suitable closure 32 therein. 70 75

In practical use the electrical current is conducted by the conducting stem 16 to the center or positive electrode 25 and is discharged across the gap between the edge 27 and the face or edge 7, resulting in a jump spark which is full and strong as required to reliably ignite the explosive charge in the 80 engine cylinder. The advantages of the large jump spark for high power engines and consequent relative gain in efficiency is well understood and results from the novel construction and relative arrangement of 85 the electrodes. Carbon deposits are prevented by explosions in the hollow shank. The heat generated by the explosions causes air to circulate in the bore 29 of the conducting stem in case the bore is open 90 to the atmosphere which it may be in some cases, resulting in the center electrode being prevented from becoming excessively hot. In case the liquid 30 be present in the bore 95 29 the heat causes the liquid to expand and rise in the bore, so that the heat is carried upward to the cooler upper portion of the stem and the insulator, the cooled liquid being repeatedly condensed and descending to repeat the process. 100 105

Having thus described the invention, what is claimed as new is—

1. In a spark plug comprising a shell threaded upon its exterior and constituting one electrode, an insulating member arranged within said shell, a stem extending through said insulating member and terminating in a disk, the lower or outer face of which is flat, the inner face thereof being a shallow cone, said disk having a plurality of apertures therein, the periphery of said disk being spaced from the lower inner edges of the shell, and means for positioning the stem within the insulating member. 110 115 120

2. A spark plug comprising a shell and constituting one electrode, an insulating member arranged within said shell, a stem extending through said insulating member and terminating in a disk, the lower outer face of which is flat, the inner face of which is slightly coned, said disk being concentrically spaced within the inner edges of the shell end and provided with a plurality of openings. 125 130

3. In a spark plug, the combination of a shell with an externally-threaded shank having a bore therein that has an outwardly-flaring orifice, a hollow insulating core secured in said shell, a hollow conducting stem secured in and extending through said core, a disk fixed on one end of said stem and having its peripheral edge located opposite and closely adjacent to the larger outer portion of said flaring orifice, the center of said disk being a closure to one

end of the hollow stem, a plug in the opposite outer end of said stem, and a connecting nut secured to the outer end of said stem and covering said plug.

15

In testimony whereof, I affix my signature in presence of two witnesses.
